DESIGN FOR AN AUTOMOBILE HEATER OR SIMILAR ARTICLE

Edmund E. Hans, Detroit, Mich.

Application February 20, 1937, Serial No. 67,773

Term of patent 14 years

To all whom it may concern:

Be it known that I, Edmund E. Hans, a citizen of the United States, residing in the city of Detroit, county of Wayne, and State of Michigan, have invented a new, original, and ornamental Design for an Automobile Heater or Similar Article, of which the following is a specification, reference being had to the accompanying drawing, forming part thereof, in which

The figure shows a perspective view of the front and side portions of my new design for an automobile heater.

The far side of the heater, not shown in the drawing, has the same appearance as the side shown, and the bottom edge, also not shown, is substantially the same as the top edge illustrated.

I claim:

The ornamental design for an automobile heater or similar article substantially as shown and described.

EDMUND E. HANS.
